UNITED STATES PATENT OFFICE.

SIMON W. FARBER, OF BROOKLYN, NEW YORK.

PORTABLE LAMP.

Application filed April 11, 1923. Serial No. 631,292.

To all whom it may concern:

Be it known that I, SIMON W. FARBER, a citizen of the United States, residing at Brooklyn, city of New York, in the county 5 of Kings and State of New York, have invented certain new and useful Improvements in Portable Lamps, of which the following is a specification.

This invention relates to improvements in 10 lamps of the type shown in my previous U. S. Patent No. 1,266,241.

My invention relates to a new and improved portable lamp.

One of the objects of my invention is to 15 provide a portable lamp which can be placed upon or suitably clamped to any convenient support and which can be quickly and economically manufactured.

Another object of my invention is to provide 20 a lamp of the above mentioned type comprising a plurality of movable parts which can be relatively adjusted so as to throw the light in a great number of directions.

25 Another object of my invention is to provide a lamp of the before mentioned type in which the parts will remain in any position to which they have been adjusted.

Another object of my invention is to combine 30 a friction device, embodying a spring, in a lamp structure of the above mentioned type so that said spring will serve as a friction device to hold the adjusted parts firmly, but movably, in position.

35 Other objects of my invention will be set forth in the following description and drawings which illustrate a preferred embodiment thereof.

Fig. 1 is a side elevation.

40 Fig. 2 is a side elevation partially in section and showing the parts in a different relative position.

Fig. 3 is a rear view of Fig. 2.

Fig. 4 is a detail sectional view.

45 Fig. 5 is a top view of the base of the lamp, a portion thereof being broken away.

Fig. 6 shows my lamp applied to an automobile so as to serve as a "trouble" lamp, although my invention is not restricted to 50 this purpose.

The base portion of the lamp is comprised of an upper clamp 1 and a lower clamp member 2, the rear 3 of the lower clamp member 2 being substantially flat and the 55 rear 4 of the upper clamp member 1 being preferably curved.

The upper clamp member 1 has two slots or openings 5 and 6 formed therein and the adjacent ends of these slots are provided with two upwardly stamped flanges 7 and 60 the other ends of the said slots, which may be called the remote ends for convenience, are provided with two downwardly stamped flanges 8.

It can thus be seen that the top member 1 65 together with the flanges 7 and 8 thereof can be formed from a single piece of material and by the use of suitable dies so that the structure is very rigid and can be made very quickly and economically since the material for the flanges 7 and 8 is secured from that part of the upper member 1 which is stamped out of the slots 5 and 6.

The bottom member 2 is provided with two upwardly stamped flanges 9 which are 75 adapted to be located closely adjacent the flanges 8 when the parts are assembled.

The flanges 8 and 9 are suitably perforated so that a spindle 10 can be passed through them to connect the two clamp 80 members 1 and 2 so that they can be turned or partially revolved with respect to each other.

In order to keep the parts normally in the position shown in Fig. 1 for example, 85 a coil spring S is provided upon the spindle 10 and this is provided with an upper portion 11 which normally bears against the upper member 1, and with two rearwardly inclined ends 12.

90 It is obvious that the base portion of the lamp constituted by the two clamping members can rest upon any suitable support, such as shown in Fig. 1, for example, or they can clamp around any suitable supporting member M shown in Fig. 2, such as for example, an automobile, as shown in Fig. 6. The standard 14 of the lamp is revolvably connected to the member 7 by means of a construction similar to that 100 shown in Fig. 4 and which represents the manner in which the base of the lamp socket is connected to the standard 14. As clearly shown in Fig. 3, the standard 14 fits between the members 7 and is pierced at the bottom thereof so that it can be connected to the said member 7 by a threaded pin 15 having the head 16' and the nut 16.

105 The standard 14 fits relatively loosely between the stiff upright members 7 and is 110 adjustably held in position by means of a friction device similar to that illustrated in

Fig. 4. Fig. 4 shows the standard 14 connected at the upper end thereof to a U-shaped bracket 18 having two depending arms which are perforated. The perforations of the bracket 18 can be aligned with a corresponding bore or perforation at the upper end of the standard 14.

As can be clearly seen from Fig. 4 one side of said bore, which may be the right hand side thereof, has a diameter which is only slightly greater than the diameter of the pin 20 which corresponds to the pin 15 shown in Fig. 3 and has a screw head 21.

The other side of the said bore, namely the left hand side, as illustrated in Fig. 4, has a bore large enough to permit the entrance of the friction spring 19. The pin or bolt 20 which may be suitably threaded for its entire length or only a small portion of its length has a nut 23 whereby the arm of the bracket 18 may be firmly secured in position, as shown in Fig. 4.

The bracket 18, while it is made of stiff material is somewhat resilient so that the arms thereof are bent inwardly to compel them to assume the position in Fig. 4 and the resilience of these arms tends to force them outwardly and against the screw head 21 and the nut 23. This frictional effect is further increased by the friction spring 22 which, as shown in Fig. 4 tends to force the left arm of the bracket 18 against the nut 23. Hence there is a substantial frictional effect between the bracket 18 and the adjacent parts of the standard so that the parts remain in any relative position in which they are placed and it is further to be noted that this frictional device thus provided, is practically free from any wear and tear and subsequent loosening of the parts and loss of the frictional effect which is produced in other types of frictional devices by constant use.

The lamp socket 24 has the bayonet joint 45 25 and terminals 26 and in itself may be of any old and well known construction, so that it is only diagrammatically illustrated in the drawings, as I do not wish my invention to be limited to any particular type of lamp socket.

The said socket 24 has the bottom thereof internally threaded and the bottom of the socket is adapted to rest upon the ring shaped bottom 27 of the bracket 28 which movably supports the reflector 29. A bolt or nut 30 having the shape shown in Fig. 24 is adapted to firmly hold the socket 24 in position.

The reflector 29 which is made of any suitable material has an opening to admit the socket 24 and, as clearly shown in Figs. 1 and 4 it is provided with a bracket 28 secured thereto by rivets 30 or other suitable means. This bracket 28 and the shade 29 can freely revolve about the axis of the sock-

et 24, even though the socket 24 is firmly held in position and does not revolve therewith, because of the shape of the nut 30.

It is obvious from Fig. 4 that the said nut 30 has a lateral enlargement or bearing 70 flange which abuts the underside of the bracket 18 so that the socket is firmly locked into position without exerting any frictional effect upon the ring shaped bottom 27 of the bracket 28. 75

In Fig. 6 this device is illustrated as being applied to an automobile to provide light for changing a tire or the like and it is obvious that due to the adjustability of all the parts and the firm and reliable frictional devices provided that the light provided by the lamp can be projected in any direction. 80

The frictional joints provided at the bottom of the standard and at the top thereof afford a very wide range of adjustment in 85 one plane and a revoluble mounting of the reflector provides a complete adjustment in a plane at right angles to the plane of movement of the said standard 14.

It will be noted that the spring 19 shown in Fig. 4 fits tightly within the bore of the standard 14 so that it exerts a frictional effect. Before the spring 19 is compressed into the position shown in Fig. 4 its outer diameter may be slightly less than that of the bore in the standard 14, but when the spring 19 is firmly compressed into position, so that the adjacent turns thereof touch each other, the outer diameter of the said spring 19 becomes enlarged so as to secure the frictional effect before mentioned. 95 100

It is also preferable to have the pin 20 fit tightly within the spring 19.

A similar construction is found at the lower part of the standard 14 in which a coil spring similar to friction spring 19 is located in a bore at the lower part of the standard 14. The members 7 serve to confine the said spring. A hole H can be provided in the lower member 2 so that the lamp can be 110 hung on a nail or the like.

I claim:

1. A lamp support comprising a base portion consisting of two pivotally connected clamping members, the first of said members having a pair of tongues projecting outwardly and stamped out therefrom and a second pair of such tongues projecting inwardly, a standard connected to said outwardly projecting tongues and located between them, the second of said members also having a pair of tongues, and means for pivotally connecting the tongues of said second member to the inwardly projecting tongues of said first member, and a lamp socket and reflector connected to said standard. 115 120 125

2. In a lamp support comprising a base, a standard connected to said base and a lamp socket and reflector connected to said 130

standard, said lamp socket having a support adjacent the said bore having holding portions thereof adapted to be located 30 adjacent the ends of said bore, a spindle passing through said bore and holding portions and forming a pivotal connection, a coil spring under compression located on said spindle and in said bore, and means 35 for holding said spindle in position.

5. A device according to claim 4 in which said spring fits tightly in said bore so as to have a frictional hold therein.

10. The neck of said lamp socket to hold it in position, said nut projecting through the annular end of said second bracket member, said bracket member fitting loosely on said nut between the neck of said socket

15 and said first mentioned bracket member.

3. A device according to claim 2 in which said nut has a flange which is adapted to abut the adjacent part of said first-mentioned bracket member, and said neck has 20 a lateral flange, the annular end of said second bracket member fitting between said first mentioned bracket member and said lateral flange.

4. In a lamp support comprising a base, 25 a standard connected to said base, and a lamp socket and reflector connected to said standard, said standard having a bore formed therein, the first part of said lamp

6. In a lamp support comprising a base, 40 a standard connected to said base, and a lamp socket and reflector connected to said standard, said standard having a bore formed therein, the part of said lamp support adjacent to said bore having holding 45 portions thereof adapted to be located adjacent the ends of said bore, a spindle passing through said bore and connected to said holding portions and friction means located in said bore and connected to said spindle 50 and adapted to frictionally resist the movement of said adjacent part of said support with respect to said standard.

In testimony whereof I hereunto affix my signature.

SIMON W. FARBER.
